UNITED STATES PATENT OFFICE

165,819

CRACKER TRAY

Charles O. Bliss, Los Angeles, Calif.

Application February 13, 1951, Serial No. 14,205

Term of patent 14 years

(Cl. D44—10)

To all whom it may concern:

Be it known that I, Charles O. Bliss, a citizen of the United States, residing in Los Angeles, in the county of Los Angeles and State of California, have invented a new, original, and ornamental Design for a Cracker Tray, of which the following is a specification, reference being had to the accompanying drawing, forming a part thereof.

Fig. 1 is a perspective view of a cracker tray embodying my new design;

Fig. 2 is a side elevational view thereof;

Fig. 3 is a transverse sectional view taken on the line 4—4 of Fig. 3.

I claim:

The ornamental design for a cracker tray, as shown.

CHARLES O. BLISS.
